US0D1023132S

(12) **United States Design Patent** (10) **Patent No.:** **US D1,023,132 S**
Liu (45) **Date of Patent:** **** Apr. 16, 2024**

(54) **LABEL PRINTER**

(71) Applicant: **Wuhan Jingchen Intelligent Identification Technology Co., Ltd.**,
 Wuhan (CN)

(72) Inventor: **Xiong Liu**, Hanchuan (CN)

(73) Assignee: **WUHAN JINGCHEN INTELLIGENT IDENTIFICATION TECHNOLOGY CO., LTD**, Wuhan (CN)

(**) Term: **15 Years**

(21) Appl. No.: **29/866,234**

(22) Filed: **Sep. 2, 2022**

(30) **Foreign Application Priority Data**

Jul. 28, 2022 (CN) 202230487413.2
 (51) **LOC (14) Cl.** **18-99**
 (52) **U.S. Cl.** ..... **USPC D18/19**

(57) **CLAIM**

The ornamental design for a label printer, as shown and described.

DESCRIPTION

FIG. 1 is a perspective view of a label printer showing my new design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view thereof.

The broken lines depict portions of the article that form no part of the claimed design.

1 Claim, 7 Drawing Sheets
